(57) **CLAIM**

The ornamental design for a consumable for quality control machine in nuclear medicine as shown and described.

DESCRIPTION

1. Consumable for quality control machine in nuclear medicine

1.1: Top;

1.2: Bottom;

1.3: Cross sectional;

1.4: Left;

1.5: Front;

1.6: Back; and

1.7: Perspective.

The design is a consumable for quality control machines in nuclear medicine to be used as a consumable.

In the drawings:

- the broken lines with equal size dashes illustrate features of the consumable for quality control machine in nuclear medicine that form no part of the claimed design; and
- the broken lines with a dash-dot-dot pattern indicate a boundary between curvatures.
